COMBINED TRAY AND LIGHT HOUSING

Ralph F. Chambers, Decatur, Ga., assignor to Gladwin
Plastics, Inc., Atlanta, Ga., a corporation of Georgia

Filed May 3, 1960, Ser. No. 60,429

Term of patent 14 years

(Cl. D80—11)

FIG. 1

FIG. 2

FIG. 3

FIG. 1 is a perspective view taken from one side and end of a combined tray and light housing embodying my new design;

FIG. 2 is a perspective view taken from the side and end opposite those shown in FIG. 1;

FIG. 3 is a top plan view thereof; and

FIG. 4 is a side elevation view thereof.

I claim:

The ornamental design for a combined tray and light housing, substantially as shown.
